UNITED STATES PATENT OFFICE

HENRI CHIREIX, OF PARIS, FRANCE, ASSIGNOR TO SOCIETE FRANCAISE RADIO-ELECTRIQUE, OF PARIS, FRANCE, A CORPORATION OF FRANCE

ANTENNA ARRANGEMENT

Application filed April 28, 1931, Serial No. 533,397, and in France May 6, 1930.

The present invention relates to antenna arrangements and more particularly to directional antenna arrangements for use on short waves.

One of the difficulties met with in the transmission of signals by means of short waves resides in the manifestation of "fading" or vanishing of the signals. One of the causes of fading resides in the rotation of the plane of polarization of the waves incident on a receiving antenna, the strength of the received signals varying more or less as this plane of polarization differs more or less from the plane of polarization for which the receiving antenna has been constructed.

The object of the present invention is to provide a simple antenna arrangement adapted to receive waves equally well whatever the plane of polarization of said waves may be.

To consider the case of a vertical antenna element half a wave length long for example, an incident wave whose electric field makes an angle φ with the vertical will induce an electromotive force of the form:

$$e_1 = A \cos \varpi t \cos \varphi$$

where ϖ is the high frequency oscillation and t the time.

If a second identical but horizontal antenna element is placed one quarter of a wave length behind the first mentioned element in the path of the incident waves the electromotive force induced in this element will be:

$$e_2 = A \sin \varpi t \sin \varphi$$

whence

$$e_1 + e_2 = A (\cos \varpi t \cos \varphi + \sin \varpi t \sin \varphi) = A \cos (\varpi t - \varphi)$$

If this second element is followed by a third element which is again vertical and located one quarter wave length behind the second, that is to say half a wave length behind the first, there will be obtained an electromotive force:

$$e_3 = -A \cos \varpi t \cos \varphi$$

Finally if there is arranged a fourth element this time horizontal and again one quarter wave length behind the third, that is to

say half wave length behind the second, there will be obtained an electromotive force:

$$e_4 = -A \sin \varpi t \sin \varphi,$$

whence:

$$e_3 + e_4 = -A (\cos \varpi t - \varphi).$$

It will be seen from the above analysis that in order to combine the electromotive forces induced in the several antenna elements the third and fourth elements should be connected in opposition to the first and second elements in order that the several electromotive forces be additive.

Obviously it is possible to increase the number of antenna elements to any desired extent. A preferred antenna arrangement in accordance with the invention is illustrated in the accompanying drawings, in which Figure 1 is a perspective elevation viewed from one end; Figure 2 a side elevation and Figure 3 a plan view.

Referring to Figure 1 an element AB (of length equal to a half wave) is arranged in a vertical plane, parallel to the direction of wave propagation but inclined in this plane such that the vertical projection of the point B on a horizontal plane passing through A is one quarter wave length behind the point A.

It obviously follows, on referring to Figure 2, that the angle θ between AB and the vertical BB' is equal to 30°.

A second element BC (Figure 1 and Figure 2) is connected to the element AB in a horizontal plane but inclined in this plane such that the projection of the point C on the vertical plane containing the element AB is one-quarter wave length behind the point B. That is to say that the element BC is inclined to the horizontal line passing through B and lying perpendicular to the plane of Figure 2 at an angle of 30°, further elements CD, DE, EF, etc., are arranged in succession in a similar manner.

To put the matter in another way, the construction of the antenna may be defined by saying that it is constructed in the form obtained by winding a continuous wire on a

- prism having a square base, whose sides are equal to $\frac{\lambda}{2} \cos 30^\circ$, the axis of the prism 70
⁵ being parallel to the direction of propagation of the waves, and each linear element having a length equal to $\frac{\lambda}{2}$ where λ is the 75
¹⁰ wave length for which the antenna is designed.

It will easily be seen that such an arrangement fulfills the conditions enumerated above. In effect the phase of the resultant 80
¹⁵ electromotive force induced in the element

- BC is displaced by an angle $\frac{\pi}{2}$ with respect 85
²⁰ to that induced in the element AB; that induced in the element CD is in phase opposition with that induced in the element AB (one half wave behind) and so forth. The electromotive force induced in the elements AB and CD both tend to cause current to 90
²⁵ circulate in the direction of the arrows in accordance with the law of excitation by stationary waves (the phase of the current reverses at each current node, that is to say, at each peak).
- 30 The number of elements is not limited to that illustrated and the greater the number of elements employed the more is the directive effect of the antenna accentuated.

In the case of an incident wave arriving 95
³⁵ perpendicular to the plane of Figure 1, the elements AB CD EF GH etc., constitute in effect an alignment of antenna the effects of which are additive. Similarly the elements BC ED FG HI constitute a second alignment 100
⁴⁰ at right angles to the first, giving a concentration in the vertical plane. The distance in the direction of propagation of the wave between AB and CD being one half wave length or between AB and EF a whole wave 105
⁴⁵ length, such an antenna does not act as a reflector inasmuch as it receives equally well waves which are incident at either end thereof.

50 The energy received may be tapped by any suitable coupling preferably in the middle of the conductor ABCDEFGHI etc.

Naturally such an antenna may equally well be employed for transmission. Obviously the structure described above may be 110
⁵⁵ turned round on its longitudinal axis through any angle so that the elements AB and BC in place of being alternately horizontal and vertical are disposed obliquely. The only condition to be fulfilled is that the direction of propagation of the radiation to be 115
⁶⁰ received or transmitted should be parallel to the longitudinal axis of the antenna.

A plurality of identical systems may be 120
⁶⁵ employed in combination further to increase the directive properties thereof.

It should be understood moreover that the square coil structure does not exclude variations producing equivalent effects. The wire may be wound on any prism having a regular polygonal base or even on a circular cylinder, the essential and general condition to be observed being that the length of one turn of the developed "coil" should be twice the length of the wave and the pitch of the coil 125
⁷⁵ equal to the length of the wave, the orientation of the axis of the coil being that of the propagation of the wave.

Claims:

1. Aerial comprising a number of series connected sections in the form of an helix 80
⁸⁰ each winding of which has a perimeter equal to twice the wavelength and the pitch of which is equal to one wavelength.
2. Aerial comprising a number of series connected equal sections, the length of each section being equal to half a wave length, 85
⁸⁵ each section lying in a plane at right angle with the plane of the preceding section and the whole forming an helix the pitch of which is equal to one wavelength. 90
